UNITED STATES PATENT OFFICE.

JOSEPH ANTONUCCIO, OF FRUITVALE, CALIFORNIA.

WATER-HEATER.

1,077,579.

Specification of Letters Patent.

Patented Nov. 4, 1913.

Application filed September 5, 1911, Serial No. 647,484.

To all whom it may concern:

Be it known that I, JOSEPH ANTONUCCIO, citizen of the United States, residing at Fruitvale, in the county of Alameda and State of California, have invented a new and useful Water-Heater, of which the following is a specification in such full and clear terms as will enable those skilled in the art to construct and use the same.

10 This invention relates to a water heating dome for domestic boilers, and its object is to provide a proficient and rapid water heater for domestic boilers, which will avoid many of the defects of the ordinary forms 15 of heaters, and which will particularly avoid heating the outside of the boiler shell surrounding the burner to such a temperature as to injure the wood-work adjacent the boiler.

20 Another object of the invention is to provide a heating dome which will have such a number of openings from one side of its shell to the other, as to deliver either hot water or steam as may be necessary.

25 The delivery of steam through the dome is accomplished by increasing the number of openings through the shell whereby more metal is exposed to the action of the heater.

Another advantage of this invention lies 30 in the possibility of delivering either steam or hot water from the heating drum as may be desired, by a change in position and the number of openings through the shell of the dome. For example, with a heating dome 35 of a given size it is possible to increase the temperature of the water delivered therefrom very considerably by an increase in the number of openings through the dome, in which event, if sufficient heat is used it is 40 very easy to deliver steam from the heater. If a heater such as is shown in Figure 4 is used, the openings will direct the flame therethrough very readily, but the extent of metal in contact with the water is not sufficient 45 to deliver steam as a product without unduly increasing the heat applied to the dome.

In the drawings in which the same number of reference is applied to the same portion throughout the several views, Fig. 1 is a side elevation partly in section of one form of the water heating dome. Fig. 2 is a side elevation partly in section of a similar water heating dome, showing the cold water inlets thereto at the sides. Fig. 3 is a view 55 partly in section of a boiler, and the water

heating dome showing the relative position thereof. Fig. 4 is a side elevation of a slightly modified form of water heating dome, and Fig. 5 is a partly sectional view of a boiler, and the dome shown in Fig. 4.

The water heating dome comprises a more or less conical corrugated shell 1, having openings 2 from the outside portion of the shell, to the inner portion of the shell 3 placed in several different series. The outer and inner walls of the shell are separated far enough to permit the heating of a suitable quantity of water therein, which water may be fed to an inlet pipe 4, or should it be necessary to use two inlet pipes, the plug 5 may be removed, and another inlet pipe may be attached thereto. At the top of the dome is outlet pipe 6.

The water heating dome is supported 75 within the boiler 7, and below a conical bottom 8, a flue 9 extending from the top of the conical bottom 8 through the top of the boiler. The pipe 4 is connected to a suitable elbow 10, which in turn is connected to 80 a pipe 11 passing through the side of the boiler. This pipe 11 is connected to a T 12, and the latter is connected with the cold water feed pipe 13, and another pipe 14 leading into the lower part of the boiler to supply cold water therethrough. A burner 15 is suitably supported below the heating dome 1. It will be noted that the flame from the burner 15 will pass up through the openings in the heating dome 1, while some 90 of it passes around the outside thereof, but the larger quantity will pass through the dome thus drawing a large quantity of water into contact with the flame for the purpose of heating the water. It will also be noted that what flame therefrom does pass outside of the dome 1, will strike the conical bottom 8, and since this is protected by the water within the boiler, the outside of the boiler will not become red hot, as is 95 the case with boilers not so protected.

Figs. 2, 4 and 5 show slight modifications of the invention. Fig. 2 shows the water dome 1 with side inlets 16 and 17 as is sometimes desired. In Fig. 4, the dome 18 is 105 provided with only four flame outlets 19, said outlets being about one-third the distance below the top of the dome. This form is provided with a plug 5 and inlet pipe 4, same as dome shown in Fig. 1, and is connected to the boiler in exactly the same way as shown in Fig. 5.

Having thus described my invention what I claim as new and desire to secure by Letters Patent of the United States, modifications within the scope of the claims being expressly reserved, is as follows:—

- 5 1. A water-heater comprising a hollow heating drum having an inner concave wall and an outer convex wall and providing a conical annular water chamber therebetween, inlet and outlet pipes connected therewith at the bottom and top respectively, and said drum having a plurality of upwardly extending channels passing transversely therethrough.
- 10 15 2. A water-heater comprising a hollow heating drum having an inner concave wall

and an outer convex wall and providing a conical annular water chamber therebetween, said walls being annularly corrugated, inlet and outlet pipes connected therewith at the bottom and top respectively, and said drum having a plurality of upwardly extending channels passing transversely therethrough.

In testimony whereof I have hereunto set 25 my hand this 23rd day of August A. D. 1911, in the presence of the two subscribed witnesses.

JOSEPH ANTONUCCIO.
